UNITED STATES PATENT OFFICE.

MICHAEL S. COLEMAN, OF NEW YORK, N. Y.

MINE-SHAFT ELEVATOR.

SPECIFICATION forming part of Letters Patent No. 289,231, dated November 27, 1883.

Application filed October 1, 1883. (No model.)

To all whom it may concern:

Be it known that I, MICHAEL S. COLEMAN, of the city, county, and State of New York, have invented a new and useful Improvement 5 in Mine-Shaft Elevators, of which the following is a full, clear, and exact description.

Reference is to be had to the accompanying drawings, forming a part of this specification, in which similar letters of reference indicate 10 corresponding parts in all the figures.

Figure 1 is a side elevation, partly in section, of my improvement. Fig. 2 represents one of the screws at the upper ends of the guide-ropes enlarged. Fig. 3 is a sectional 15 plan view of an elevator-carriage, taken through the line *xx*, Fig. 1. Fig. 4 is a plan view of an elevator-carriage.

The object of this invention is to facilitate the working of mine and tunnel shafts by providing means for the convenient and speedy 20 removal of the elevator appliances when blasts are to be fired.

The invention consists of carriages traveling upon guide-ropes extending down the shaft, and provided with means for readily attaching, detaching, tightening, and slackening them, as will be hereinafter fully described.

A represents a mine-shaft.

30 B is the elevator-frame erected over the mouth of the shaft A.

C are the elevator-carriages, to the tops of which are attached the ends of the hoisting-ropes D. The hoisting-ropes D pass over 35 guide-pulleys E, pivoted to the frame B, and around the hoisting-drum F, to the shaft G of which motion is given from a steam-engine or other suitable power.

H are the platform-timbers, which are bolted 40 to the rocks at the bottom of the shaft A in the ordinary manner, and to which are attached eyebolts I, to receive the hooks J attached to the lower ends of the guide-ropes K. Four guide-ropes, K, are used for each carriage C, and the 45 upper ends of the said ropes are connected by swivels L with clevises M, attached to the lower ends of hand-screws N, which pass through nuts attached to or screw-bolts formed in the upper bars of the frame B. The heads of the 50 screws N are provided with levers O or other convenient means for turning them to tighten or slacken the guide-ropes K. To the lower corners of the carriages C are attached brack-

ets P, the outer ends of which project and have holes formed through them to receive the guide-ropes K. To the tops of the carriages C are attached cross-bars Q, the ends of which project at the corners of the said tops, and have holes formed in them, directly over the holes in the brackets P, to receive the guide-ropes K. With this construction, when the guide-ropes K have been drawn taut, the carriages C will move up and down upon them with as much ease and safety as they would upon rigid guide-posts. 55

In using the improvement, when a blast is to be fired the guide-ropes K are slackened, the hooks J are unhooked, and the said ropes K and the carriages C are raised to such a height that they will not be liable to be injured by the blast. When the blast has been shot, the carriages C and ropes K are again lowered, the hooks J are hooked into the eyebolts I, the screws N are turned to tighten the said ropes K, and the elevator is again 60 ready for use, the whole operation of removing the ropes and carriages and replacing them requiring but a few minutes, so that much 65 time and labor will be saved.

Having thus described my invention, I claim 70 as new and desire to secure by Letters Patent—

1. In a mine-shaft elevator, the combination, with the top frame, B, the bottom frame, H, and the carriage-frame C, of the guide-ropes K, the hooks and eyebolts I J, and the 75 screws N, substantially as herein shown and described, whereby the carriage will be guided in its up and down movements, and the guides can be readily removed and replaced, as set forth.

2. In a mine-shaft elevator, the combination, with the top frame, B, the bottom frame, H, and the carriage-frame C, of the guide-ropes K, the hooks and eyebolts I J, screws N, levers O, swivels L, and clevises M, substantially as and for the purpose set forth. 85

3. In a mine-shaft elevator, the combination of the top frame, B, the bottom frame, H, the carriage-frame C, the ropes K, the hooks and eyebolts I J, screws N, the hoisting-ropes D, pulleys E, and the drum F, substantially as and for the purpose set forth. 90

MICHAEL S. COLEMAN.
